UNITED STATES PATENT OFFICE.

JAMES J. COOK, OF JERSEY CITY, NEW JERSEY.

THERMO-ELECTRIC GENERATOR.

1,083,191.

Specification of Letters Patent. Patented Dec. 30, 1913.

Application filed March 25, 1911. Serial No. 616,825.

To all whom it may concern:

Be it known that I, JAMES J. COOK, a citizen of the United States, residing at Jersey City, in the county of Hudson and State of New Jersey, have invented a new and useful Thermo-Electric Generator, of which the following is a specification.

This invention has reference to improvements in thermo electric generators commonly known as a thermo electric battery or pile, and its object is to improve the efficiency of such generators or piles, and, at the same time, make them compact and especially adapted for commercial use, the thermo electric pile of the present invention having a markedly low internal resistance and being so constructed that its life is markedly prolonged.

In accordance with the present invention the thermo electric pile is made up of like elements, formed of materials well separated in the thermo electric order, joined in couples and the couples grouped into piles of any desired number of groups.

The separate elements as to form and size may be all alike and are so constructed as to provide large contact surfaces between the elements of each pair and the contact surfaces are brought into engagement by sufficiently heavy pressure to provide very low internal resistance because of such large surface and intimate contact, the union of the elements of dissimilar materials into pairs being brought about without the use of any cementing material, so that the junction is solely by contact. Moreover, the joined terminals of the piles of pairs of elements are so disposed and these elements are so formed that the ends of each element are sufficiently separated but still electrically connected, and there is produced through the ends of the pile channels for the passage of heating and cooling mediums, the passages being shaped to present a large surface to the action of such mediums.

The two ends of the pile where traversed by the passages are made alike so that either end is adapted to be traversed by a heating medium and either end is adapted to be traversed by a cooling medium, whereby a suitable heating medium may be caused to flow through the passage formed by the union of suitably pierced end members or terminals of the elements when joined into

a pile at one end of said pile, and a cooling medium may be caused to flow through the like passage similarly formed at the other end of the pile, these passages being interior to the respective ends of the pile and the heating and cooling mediums being brought into direct contact with the metals of which the elements are formed.

After a thermo electric pile has been used for some considerable time it is found that the joints deteriorate so that the output of the pile is diminished and ultimately such a pile will deteriorate to such an extent as to render it practically useless.

With the thermo electric pile of the present invention such deteriorating action is readily counteracted by a reversal of the application of the heating and cooling mediums, so that the heating medium is made to traverse the end of the pile previously subjected to the cooling medium and the cooling medium is made to traverse the end of the pile previously subjected to the action of the heating medium, the external electrical connections being properly adjusted in accordance with the change. Because of this reversal the pile is restored to its original working condition and so remains until deterioration takes place in the joints in the reverse action of the pile, when the defect may be again remedied by restoring the relation of flow of the heating and cooling mediums as at first, and such reversal may be brought about from time to time as necessary, thus rendering the life of the pile almost limitless.

The invention will be best understood from a consideration of the following detailed description taken in connection with the accompanying drawings forming a part of this specification, with the understanding, however, that while the drawings show a commercial form of the invention such showing is only some of many forms which the invention may assume, and consequently the invention is not limited to the exact showing of the drawings, but may be varied within wide limits without departing from the salient features of the invention.

In the drawings:—Figure 1 is a perspective view of a thermo electric pile constructed in accordance with the present invention. Fig. 2 is a section on the line 2—2 of Fig. 1. Fig. 3 is a section on the line 3—3 of Fig. 1.

Fig. 4 is a section on the line 4—4 of Fig. 3. Fig. 5 is a plan view of one of the elements of the pile. Fig. 6 is a plan view of an insulating washer used to separate the connected ends of each pair of elements from the like connected ends of adjacent pairs of elements. Fig. 7 is a plan view of an insulating anchor member employed in elongated piles. Fig. 8 is an elevation with some parts in section of a modified form of the invention. Fig. 9 is a plan view of the structure shown in Fig. 8 with parts in section on the line 9—9 of Fig. 8. Fig. 10 is a plan view of a thermo electric element used in the pile of Figs. 8 and 9. Fig. 11 is a plan view of an insulating washer used in connection with the element of Fig. 10. Fig. 12 is a plan view with one end in section of a modified form of element differing from that of Figs. 5 and 10. Fig. 13 is a section on the line 13—13 of Fig. 12. Fig. 14 is a plan view of a terminal connector used in connection with the pile. Fig. 15 is a plan view of an intermediate connector for electrically coupling two adjacent groups of elements. Fig. 16 is a section similar to Fig. 3, with parts in elevation, of a structure wherein but a single group of elements constitutes a pile. Fig. 17 is a plan view of an element which may be used in connection with the structure of Fig. 16. Fig. 18 is a plan view of one of the heads used in the construction shown in Fig. 16.

Referring to the drawings, and first to the structure of Figs. 1 to 6, there are shown two heads 1, 2, which may be simple metallic blocks of rectangular or other form, each with one face substantially plane and the other face, which in the assembled generator, constitutes the outer face of the block, provided with a centralized boss 3, each boss 3 and the respective head block 1 and 2 being provided with passages leading from the outer face of the boss to the inner face of the block, and these passages are traversed by bolts 4, 5, respectively, it being understood that usually two bolts are sufficient in the smaller types of thermo electric generators, while more bolts are needed in the larger types. These bolts may be employed as terminals for the generator and since for strength and rigidity the heads 1 and 2 are ordinarily made of metal, the bolts are insulated from the respective heads by insulating sleeves 6, 7, respectively, each bolt being insulated from one head by a sleeve 6 and from the other head by a sleeve 7 and the latter is made sufficiently long to not only extend through the corresponding head but to extend substantially the full length of the bolt toward the other head, the sleeve 7 terminating at an enlargement 8 formed on or secured to the bolt near the inner face of the corresponding head for a purpose which will hereinafter appear.

Each bolt has applied thereto at each end a nut 9 between which and the adjacent boss 3 there is interposed a washer 10 of insulating material, and, if desirable, a washer 11 of metal or other suitable resisting material, while at one end each bolt has applied thereto an additional nut 12 and washer 13 whereby the nut 12 in conjunction with the washer 13 and the nut 9 may be utilized as a binding post or connecting means for an external conductor indicated at 14 in Fig. 4.

The bosses 3 serve to stiffen the heads 1 and 2 and the bolts 4 and 5 serve as clamping means for forcing the heads one toward the other to engage intermediate members and hold them together with any degree of pressure which the bolts will permit.

The thermo electric pile is composed of elements 15, 16, respectively, one of which, say the element 15, is shown separately in Fig. 5, and as the contour of both elements is the same a description of the element 15 as shown in Fig. 5 will answer as well for the element 16, the only difference between the two elements being that one is made of a metal or alloy at or near one end of the thermo electric series and the other is made of another metal or alloy at or near the other end of the thermo electric series. The two metals usually employed are antimony and bismuth, but the present invention is by no means limited to these two metals, since other metals or alloys may be employed, the particular composition of the elements depending upon the conditions to be met. As an example of alloys, an alloy of antimony and selenium with the antimony predominating may be employed for the positive element and an alloy of bismuth and aluminum may be employed for the negative element, but while these alloys produce excellent results they are here given simply as examples.

Each element comprises a central web or junction strip 17 and terminal heads or enlargements 18, the latter being circular, as indicated in the drawings or any other appropriate shape, the circular shape being generally preferred. Each element may be of the same thickness throughout, or the central web may be thinner than the terminal portions or heads as will hereinafter appear with reference to Figs. 12 and 13, but in each instance the heads are of relatively large diameter and flat and of the same thickness throughout from the mid line of the element to both faces of the head.

Each head 18 is pierced by a centralized passage 19, the walls of which may be serrated, as indicated at 20, although the particular formation of the walls is not material to the present invention, except that it is desirable that the walls of the passage 19 present as large a surface as possible without too much reduction of the width of the metal between the passage 19 and the outer

70

periphery of the head 18. The web 17 should be as great or greater in width than the distance between the walls of the passage 19 and the outer periphery of the head 18, so that the web 17 will add practically nothing to the resistance of the element.

The positive and negative elements have the heads 18 in actual contact at one end and the heads 18 at the other end in actual contact with the like heads of the next adjacent elements, while the heads 18 of a pair of elements remote from those in actual contact are separated by a washer 21 of insulating material, preferably of a refractory nature, and one unaffected by liquids or the vapors of liquids, mica being preferred because of its insulating, refractory and inert nature. Mica is also to be preferred because it may be obtained and used in very thin lamina and will withstand great pressure, the structure of the present invention, as will hereinafter appear, providing for the exercise of great pressure upon the thermo electric elements and the difference of potential being comparatively small. Where comparatively large electro-motive force is to be generated, the insulating washers 21 may be made relatively thicker, but these are structural details which need not be particularized. It is to be observed that each element 15 and 16 is identical one with the other except as to the material used and that the two heads 18 of each element are alike.

When the elements 15 and 16 are assembled in a pile, the webs 17 are slightly bent, since at one end a pair of positive and negative elements have the broad faces of the respective heads 18 parallel and in actual contact, while at the other end the heads 18 are separated by a washer 21 though still parallel and in planes parallel with the first-named heads and the pile is built up of such pairs of elements, which after being assembled are clamped between the heads 1 and 2 under such pressure exerted by the nuts 9 on the bolts 4 and 5 that those faces of the heads 18 of the elements 15 and 16 in actual contact are forced together most intimately, whereby a better union is obtained than can be obtained by the use of a metallic cement and most excellent electrical contact equal to that produced by a fusion of the metals one with the other. This manner of uniting the contacting ends of the pairs of elements of dissimilar materials has the advantage that the uncertainties of fusion or soldering are avoided, while the union may be so perfect electrically as to present no noticeable resistance whereby internal resistance of the pile even where a large number of elements are employed is so small as to permit the generation of a large current, it being commercially practicable to obtain from two hundred to three hundred pairs of elements, the number varying in accordance with the

difference in temperature of the heating and chilling mediums, a current approaching fifty amperes in volume at a pressure of about one volt, the separate elements in such a pile having the heads 18 about one and a half inches in diameter and the total length of the element being about four inches, while the thickness of each element may approximate one-eighth of an inch. The foregoing figures are to be deemed as only approximate, but are based upon results obtained from practical working structures made in accordance with the present invention.

In the structure shown in Figs. 1, 2, 3 and 4 there are three separate groups of pairs of elements united electrically into a single pile, and these groups are so placed that the webs 17 of one group are in parallel spaced relation to the webs 17 of the other groups, while the bolts 4 and 5 extend through the spaces between the outside groups and the central group and these bolts serve to firmly clamp the several groups with the contacting faces of the heads 18 engaging each other under such pressure as to form practically perfect electrical union.

Each pile is in the commercial form designed to have a certain output and the number of pairs of elements employed, as well as the number of groups into which these pairs of elements are assembled, must depend upon such output and also the space available for the piles, so that in some plants if, for instance, it be desirable that each pile should generate an electro-motive force of one volt and that the heating and cooling elements employed could be obtained with a certain temperature difference, then two or three hundred pairs of elements will be assembled in two, three or more groups between appropriately shaped heads 1 and 2, so that at the terminals of the pile with the heating and cooling fluids available there will be produced a difference of potential of one volt. The elements are so assembled that all those of a group have the passages 19 through the heads 18 on the corresponding ends of the elements in alignment and there is thereby produced a passage through each side of each group of joined elements which group is firmly held in position by the clamping action of the heads 1 and 2 engaging the opposite ends of the group and forced into firm contact therewith by the bolts 4 and 5 and their nuts 9. The opposite ends of the passages through each group are made to match passages 21^a, 22 through respective heads 1 and 2, the passages 21^a being entered from the outer face of the head 1 by pipes 23 which on one side of the head 1 are united into a single pipe 24 and those on the other side of the head 1 are united into a single pipe 25. The passages 22 are entered by pipes 26 which on one side of the head 2 are united into a single pipe 27.

and on the other side of the head 2 into a single pipe 28, and the pipes 27 and 28 each contain a valve 29.

When each group of elements contains a sufficient number of elements to considerably elongate the group, there is a possibility of the outside groups buckling, and to prevent this certain of the washers 21 may be replaced by an elongated strip 30 of mica or other suitable insulating material provided with passages 31 like the central passage through each washer 21, both of these passages 31 and the passage through each washer 21 being of a size equal to the diameter of the passage 19 through each head 18 to the extreme ends of the notches forming the serrations 20. By providing an appropriate number of strips 30 the tendency of the groups of elements to buckle in either direction is overcome.

It is usually desirable that each pile should be a unit of manageable size, although this does not preclude the construction of the piles as large as may be practicable. Since the bolts 4 may be utilized as terminals for the entire pile the terminal one of the elements 15 or 16 of a group has placed in contact therewith a connector 32 having at one end a passage 33 agreeable in size to the passage through the washers 21 and also to the passage 31 of the strip 30, so as not to interfere with the free passage through the several elements from a pipe 23 to a pipe 26 and this connector 32 has another passage 34 therethrough designed to be traversed by the bolt 4 or 5, as the case may be, in contact with the enlargement 8 thereof, an insulating washer 35 being interposed between the connector 32 and the head 1 or 2 as the case may be.

The groups of elements are united at the proper ends by other connectors 36 which in general shape may agree to the form of an element 15 or 16, having at each end a head 37 with a passage 38 therethrough like the passage 31 in the strip 30 or the passages through the washers 21, and these heads are united by a connecting web 39, which, however, may be shorter than the connecting webs 17 because the groups of elements may be in closer relation than are the ends of the individual elements.

The electric circuit is readily traced from Fig. 4 where the lead 14 may be considered as connected to the bolt 4, and this bolt is in electrical connection with the corresponding end of one of the end groups of elements by a connector 33 shown in dotted lines in Fig. 4. The circuit may then be traced back and forth to the elements of the group from end to end of the several elements until the last element at the end remote from the connector 33 is in electrical contact with a connector 36, which extends to the corresponding end of the intermediate group, whence

the circuit may be traced back and forth through the intermediate group to the other end thereof, which is the end adjacent to the connector 33, and this end of the group is coupled by another connector 36 shown in Fig. 4 in dotted lines to the corresponding end of the other end group, whence the circuit may be traced through this last named group to the end thereof remote from the connector 36 where there is applied another connector 33 leading to the bolt 5 and to this bolt 5 the other lead 14 is connected. It will thus be seen that the several elements of the pile, although in the particular showing of the figure they are assembled in three groups, are all connected in series and the voltage of the pile is that of the sum of the potential differences of all the separate pairs or couples of elements and the current which may be drawn from such a pile will depend upon the internal resistance which, as before stated, is very low.

Let it be assumed that the pipe 24 is in communication with a source of cooling medium, such as water, and that the pipe 25 is in communication with a source of heating medium, such as steam. The water may be ice water, or water at atmospheric temperature. The steam may be steam at but a few degrees above the temperature of boiling water, or it may be superheated steam at high temperature and pressure, all these conditions modifying the electrical output of the pile. The valves 29 will control the flow of the heating and cooling medium through the elements, and it will be observed that these mediums both come in direct contact with the walls of the passages 19, and since these walls are serrated or similarly formed they present comparatively large conducting surfaces to be affected by the mediums traversing the conduits formed by the aligned passages 19.

The result of the heating and cooling mediums is to highly heat one end of each group of elements and to chill the other end of such group, and there is, therefore, established a marked temperature difference between the two ends of the groups with the resultant production of an electric current. By properly controlling the flow of the heating and cooling mediums the temperature difference may be maintained irrespective of the demand for current upon the pile, the greater the demand within the capacity of the pile requiring a greater absorption of energy from the heating and cooling mediums. Where the difference of potential obtained is comparatively small the non-conductive properties of ordinary water or of condensed steam are sufficient to prevent any material loss of electric energy, because of the short circuiting of the elements by such water, but where the difference of potential is sufficiently high or

where for other reasons it is not desirable to use water or steam, oil may be substituted and may be heated to any degree of temperature desirable or if the cooling medium is wanted at less than atmospheric temperature the oil may be chilled.

It is not mandatory that the bolts 4 and 5 extend through the spaces between the groups of elements, for instead of the structure of Figs. 1 to 5, the structure of Figs. 8 to 11 may be employed. In this form the head blocks typified by the block 1^a are formed where engaged by the thermo electric elements with a circular series of passages 40 and with another passage 41 central to each circular series of passages, the passage 41 being traversed by an insulating sleeve 42 through which extends a bolt 43 having the end threaded, and to this end there is applied a nut 44, the nut engaging a washer 45, which in turn is insulated from the block 1^a by an insulating washer 46. Surrounding each series of passages 40 is a circular flange 47 extending beyond the corresponding end of the bolt 43, and to this flange is applied a cap 48 having a centrally located reducing nipple 49 into which is screwed a pipe 50 coupled to a pipe 51, which may perform the same office as the pipe 24 of Fig. 1. The other ends of the particular group of elements shown in Fig. 8 are coupled together by a bolt 43^a surrounded by an insulating sleeve 41^a and in other respects the structure is the same as described with reference to the first named ends of the elements, the block 1^a being formed with a flange 47^a like the flange 47 to which is applied a cap 48^a carrying a centralized nipple 49^a into which is screwed a pipe 50^a connected to another pipe 51^a.

The thermo electric elements of the structure shown in Figs. 8 and 9 are identical one with the other, except as to the material employed in their construction and differ from the thermo electric elements of Fig. 1 in that these elements indicated at 52 and 53, respectively, in Fig. 8, and one of which, the element 52, is shown in Fig. 10, have terminal heads 54 joined by a connecting web 55, and each head 54 is formed with a circular series of passages 56 matching the passages 40 in the clamping head 1^a. Each head 54 is provided with a centralized passage 57 for the insulating sleeve 42. The ends of the thermo electric elements to be insulated one from the other are separated by washers 58, each of which is formed with a central passage 59 and a circular series of other passages 60 in surrounding relation to the central passage 59, these passages 60 matching the passages 56 in the heads 54. The structure of Figs. 8 and 9 further differs from that of Fig. 1 in utilizing the terminal elements 52 or 53, as the case may be, as terminals of the pile by providing such ele-

ments with lugs 61 each carrying a binding post 62 for the attachment of a lead 14. In the structure shown in Figs. 8 and 9 the heating and cooling mediums are caused to pass in multiple through the circular series of passages 40, 56 and 60 which are brought in alignment one with the other to permit the flow of the heating or cooling medium as the case may be through numerous channels in each side of each group of associated thermo-electric elements. Otherwise the structure of Figs. 8 and 9 operates in the manner set forth with reference to the structure of Fig. 1.

Since some of the metals which are available for thermo electric elements are costly, it may be found in large installations advisable to use as little of these costly metals as is possible without materially affecting the efficiency of the structure. In Figs. 12 and 13 there is shown a thermo electric element wherein there is provided a web 62^a of a comparatively cheap material of good electrical conducting properties, such, for instance, as copper, and this web has at each end an annular head 63 of smaller external diameter than the diameter of the head of the thermo electric element and having a central opening 64 of greater diameter than the greatest diameter of the central passage 95 through the head of the thermo electric element, even when the latter is serrated or otherwise suitably formed. Around the copper core so provided there is cast a head 65 completely embedding the annulus 63, so that the broad surfaces of each head present a large surface of the particular metal desired for the thermo electric element and more particularly where such metal is of a costly nature. Where the metal is cheap this cost reducing expedient need not be followed. The high electric conductivity of copper makes it possible to keep down the internal resistance of the thermo electric element and at the same time provide by the enveloping head 65 a terminal metal for the element of the desired thermo electric order. While the size of each pile or thermo electric unit is not limited to any particular number or grouping of elements or pairs of elements, it is customary to form a unit capable of a predetermined or standard voltage output, so that any desired voltage may be obtained in a proper grouping of such units, which because of their similarity in action to electro-chemical batteries may be termed cells, and, therefore, to obtain any desired current to satisfy certain existing conditions a proper number of cells may be grouped in the same manner as electro-chemical cells are grouped, and the pipes conveying the heating and cooling mediums may be suitably grouped to supply all the cells simultaneously, or so many of the cells at a time as may be desirable.

After continued use for a considerable period of time there is a liability of deterioration at the joints between the elements of the couples and with thermo electric piles as heretofore constructed the output was reduced until the pile as a whole became useless.

With the present invention the source of heating and cooling mediums may be connected from the conduits leading into the cells and changed so that the heating medium may be caused to flow through that portion of the cell previously subjected to the cooling medium and the cooling medium 15 may be caused to flow through that portion of the cell previously subjected to the heating medium when the reversal of the cell thus brought about will restore the original condition and the efficiency of the cell will 20 be brought up to where it was originally. By thus reversing the cells as to the relation of the heating and cooling medium thereto from time to time at such intervals as may be necessary the life of the cell may 25 be prolonged almost indefinitely.

Since there is no positive union between the positive and negative elements making up the couples or pairs of elements of the cell or pile, the whole structure is readily 30 dismantled at any time on the removal of the clamping bolts so that repairs may be made with the greatest facility and no skilled labor is needed for the making of such 35 repairs.

35 The efficiency of the thermo pile is materially enhanced by directing the heating and cooling fluids through channels within the ends of the groups or stacks of elements, since these fluids become active to the interior of the elements, it being found that the heating or chilling, as the case may be, is more effective when it is applied interiorly to the elements and exteriorly thereto.

45 Because of the great pressure used to force the meeting surfaces of the elements into contact one with the other, they may be made smooth on their contacting faces and still be fluid tight. However, this does not preclude 50 the formation of these surfaces in other ways, whereby the electrical contact may be made extensive to correspondingly reduce the internal resistance of the pile, and the joints be made fluid tight.

55 Where it is desirable that the pile be composed of but a single group of elements, the structure of Figs. 16, 17 and 18 may be employed. In this case heads 1^b and 2^b each provided with a boss 3^a disposed longitudinally of the head are used, and these heads may be longer than wide and may conform quite closely to the shape of the elements which in Figs. 16 and 17 are indicated at 60 15^a and 16^a and one element, say the element

15^a, is shown separately in Fig. 17. In this structure the element 15^a is an elongated element with rounded ends and with the portion between the ends of substantially the same diameter throughout, which diameter may be the same as the diameter of the 70 rounded ends, although this particular shape is not mandatory, it only being necessary that the connection between the ends be of sufficient carrying capacity to maintain the low internal resistance of the pile. The elements 15^a and 16^a are alike except as to the material used, and any suitable thermo electric materials may be employed as already described with relation to the other figures. Each element, of which the element 15^a of 80 Fig. 17 may be taken as typical, is provided with a central perforation 19^a in line with the end passages 19, which are like the passages 19 of the element 15 shown in Fig. 5, although any other form of passage may be used. The heads 1^b and 2^b are provided with passages 21^a to match the conduits formed by the alined passages 19 and the passages through the washers 21 which are employed in the structure of Fig. 16 in the same manner as described with reference to the other structures and pipes 23 lead into the passages 21^a as in the other forms and for the same purpose. Each head 1^b and 2^b is formed with a central passage 66 matching 95 the combined passages 19 through the elements 15^a and 16^a when assembled, and extending through the passages 66 and 19^a is an insulating sleeve 67 traversed by a bolt 68, to the ends of which are applied nuts 9^a 100 engaging washers 11^a separated from the heads 1^b and 2^b by insulating washers 10^a. The end elements of the pile are provided with terminals 61^a for the attachment of electric conductors or any other suitable 105 means may be employed for the attachment of such conductors.

In the structure disclosed in Fig. 16 but a single bolt 68 need be used and the pile comprises but a single group of elements. The 110 operation of this structure is the same as described with reference to the other figures and the structure is susceptible of various modifications in many of its details. The pile or cell constructed in general accordance with the arrangement of Fig. 16 is particularly useful where a large output for each cell is not required and the cells may be grouped in various ways, so that any desirable output of a plurality of cells may be 115 obtained, depending upon the size of the individual cells, the number of cells employed, the electrical connections of the cells and the temperature difference between the ends of the elements, and this is also true of 120 the other forms shown and described. 125

What is claimed is:—
1. An element for a thermo-pile with the

terminal portions alike and each having a passage therethrough for a temperature controlling medium, said terminals each being of the same thickness throughout from 5 the mid line of the element toward both faces of said terminal portion.

2. A thermo-electric couple comprising two elements having like terminal portions of equal thickness throughout from the mid 10 line of the element toward both faces of said terminal portions, the terminal portions at one end of the couple being in face contact and provided with matching passages therethrough, and the couple being composed of materials differing in the thermo-electric order.

3. An element for a thermo-pile of the same thickness throughout and comprising laterally expanded terminal portions and 20 an intermediate connecting web of less width than the terminal portions, said terminal portions being provided with passages therethrough for a temperature controlling medium.

25 4. A thermo-pile comprising a group of elements each of equal thickness throughout and each having laterally expanded terminal portions with passages therethrough and constituting heads of the same thickness as the remainder of the element, said 30 elements being assembled with the heads face to face and in contact at alternate ends in series throughout the group with the heads all in planes parallel one to the 35 other, the passages through the heads where in contact forming conduits through the ends of the group for the flow of a temperature controlling medium therethrough, and terminal clamping members and connecting 40 means therein holding the contacting ends of the elements of the group in firm electrical and fluid tight engagement, said connecting means being out of the path of action of the temperature controlling medium upon the thermopile elements.

5. A thermo-pile comprising a group of elements each of equal thickness throughout comprising terminal portions or heads and a connecting web, the elements having their 50 terminal portions in alternate engagement in series throughout the group and each in a plane parallel with the planes of the other terminal portions and the connecting webs being bent to correspond to the displacement 55 of the terminal portions, and said terminal portions having matching passages, and positively acting clamping means engaging the opposite ends of the group and holding the terminal portions of the elements in electrical and fluid tight relation 60 solely by the pressure exerted by the clamping means.

6. A thermo-pile provided with elements each of equal thickness throughout with the

terminal portions in alternate engagement 65 and the intermediate portions bent to locate the terminal portions in different parallel planes, and positively acting clamping means for holding the thermo-electric elements in electric and fluid tight contact 70 solely by pressure.

7. A thermo-pile provided with a group of elements constructed for the flow of a heating medium therethrough each of equal thickness throughout with the terminal portions in alternate engagement and the intermediate portions bent to locate the terminal portions in different parallel planes, and positively acting clamping means for holding the thermo-electric elements in electric 80 and fluid tight contact solely by pressure, said clamping means extending through the thermo-pile interior thereto and out of the path of action of a heating medium on said elements.

8. A thermo-pile comprising a group of thermo-electric elements in engagement at alternate ends throughout the pile with interposed insulation at the ends not in engagement and the contacting ends of the 90 group of elements and interposed insulation having passages therethrough constituting conduits for temperature controlling mediums, each element being of equal thickness throughout with the ends in different parallel planes and the intermediate portions bent to correspond thereto, clamping heads at the ends of the thermo-pile, and clamping bolts between the heads acting through the latter on the group of elements to hold said elements in electrical and fluid tight contact 95 solely by the pressure exerted by the bolts.

9. A thermo-pile comprising a group of elements each of substantially even thickness throughout and having terminal portions 105 formed with passages therethrough, and united by an electro conducting member, the thermo electric elements being assembled in a group with alternate ends in face contact and the other ends separated by interposed insulation having passages matching the 110 passages in the ends of the thermo electric elements, all the passages at the same end of the elements uniting to constitute a conduit through the group, clamping heads for the 115 group of thermo electric elements engaging the ends of the groups and provided with passages communicating directly with the conduits through the groups, bolts extending from head to head out of the path of 120 action of a temperature controlling medium when flowing through a passage in the group of elements, said bolts exerting pressure on the heads and through them to the group of thermo electric elements, and 125 means for directing temperature controlling mediums to the heads.

10. A thermo-pile comprising a plurality

of pairs of thermo electric elements, each pair consisting of elements differing in the thermo electric order and each element of each pair being of substantially even thickness throughout and provided with laterally extended end portions and a connecting web, the end portions being traversed by passages, each pair of elements constituting a couple having the extended portions at 10 one end in face contact and at the other end separated with interposed insulation also having passages therethrough alining with the passages through the corresponding ends of the elements to form conduits through the 15 group at opposite sides thereof, clamp heads applied to the ends of the group and provided with passages communicating with the conduits through the group, means for directing temperature controlling fluids 20 through the heads and by them to and through the conduits traversing the groups, and bolts for forcing the heads one toward the other to hold the thermo electric elements in good electric contact and in fluid 25 tight relation at the passages therethrough, said bolts being located out of the path of

action of temperature controlling fluids traversing the conduits.

11. A thermo-pile comprising groups of thermo-electric elements each of substantially equal thickness throughout and comprising a central web and laterally extended terminal portions or ends having passages therethrough, the extended portions at the alternate ends of the elements of each group 30 being brought into parallel face to face contact and parallel to the planes of the ends of the other elements throughout the group, and the remaining terminal portions of the group of elements being separated by insulation, and means for holding the contacting faces and separating insulation at the ends of the elements in firm electrical and fluid tight relation.

In testimony, that I claim the foregoing 45 as my own, I have hereto affixed my signature in the presence of two witnesses.

JAMES J. COOK.
